FOLDING PAPERBOARD BOX

William Glenelg Palmer, Ilchester, Md., assignor
to The Bartgis Brothers Company, Ilchester,
Md.

Application May 14, 1943, Serial No. 486,936

1 Claim. (Cl. 229—31)

1 This invention pertains to containers and more particularly to folding paperboard boxes used for holding garments for transportation and delivery purposes. It has among its objects to provide a box foldable from a blank of paperboard or material quasi-flexible enough to be bent and retain its form, yet allowing movements and flexing of portions sufficient to permit its sides to be engaged and disengaged readily. Another object is to use a construction that will avoid the use of staples or other metal fasteners to keep overlapping portions of the sides closed securely. A further object is to have a box of this kind which has its corner portions formed to bend very readily without reducing its effective stiffness when the blank is folded into a box.

Other objects will become apparent as the invention is more fully described.

In the drawing which illustrates an example of a device exemplifying this invention:

Figure 1 is a plan view of a blank of a folding paperboard box embodying this invention, and

Figure 2 is a perspective end view of one-half of a box, in closed position.

Similar reference characters refer to similar parts throughout the drawing.

The previous forms of foldable boxes used in the past have had their corner pieces without cuts in the material where the material is bent. This arrangement bends with difficulty and cannot be closed tightly. In this invention, the corners bend readily by reason of a perforated crease arrangement, and the fact that a cut is made from the edge inwardly as described. The folded side portions serve to close tightly and make the box stiff and rigid and otherwise strengthen it. The cut portion facilitates the insertion of the parts under one another and can be utilized to reinforce the locking action of the bent over portions of the blank. No staples or the like are required and are avoided to keep points and sharp metal points from injuring the garments placed in the box for transportation.

The construction of the blank consists of a main body portion 1, with perforated creases 2 arranged along the lines of bending inwardly used for making the sides or walls 3 and 4 respectively. Cuts 5 and 6 having return directions from the creases 2 terminate at the edges 7 of the sides or walls 3, as indicated. The creases follow diagonal directions from the corners 8 of the blank, but stop spaced therefrom. The collar portions 9 of the blank are cut with a tab 10 that is cut therefrom along the lines 11 with semi-circular-slot portions 12 formed therein, at the ter-

mini of the lines. The tabs 10 are glued in place flat against the inside faces of the sides or walls 4, leaving the collar portions 9, due to the cuts 11, flexible enough to allow the bent corner squares 5 of the blank, folded as indicated in the drawing, to be inserted under them. The insertion of the bent-up corner squares, under the collars enable the latter to hold the double-thick square tightly. Before insertion the sides are vertically brought up against one another. The extending portions 13 with the apiced triangular forms are unfolded and only of one thickness. This permits the portions of folding collar near the tabs to be affected by less stresses than at the corners 15 and with less chance of being torn during the insertion. The semi-circular cuts increase this facility. The extending portions 13 have a portion 20 which may be bent up to further lock the corner pieces if desirable. A tongue 21 is extended from each side of each collar for insertion in the respective slot 22 in the side 3.

The general operation of forming blank into a box is as follows:

The collars 9 at each end are bent over on their unperforated crease lines 14 and the tabs 10 are pasted or glued down flat on the inside face 4 of the blank by adhesive 25. This leaves the collars flexible enough, through the provision provided by the cuts 12 to be bent resiliently, to receive the bent corner squares. The corner squares are easily bent on the diagonal perforated creases 2 and form a V-like structure that bends inwardly into the box and brings the sides 3 and 4 into a vertical position. This causes the corner square to bend on the crease lines 15 and 16. The portions 17 of the square near the top edge are inserted under the collar and align up with their edges 19 close to the edges 18. This stiffens the whole length of the side at the ends 40 of the box. The triangular pieces 20 project from under the collar edges and can be bent upwardly. The corners of the box are particularly strong and take up the stresses of pulling arising from the sides 3 and 4 in a very effectual manner.

45 The tongues 21, extend through the slots 22 and tend to keep the sides more rigid.

While the blank described refers only to one half of the box, it is understood that the other half that it covers or closes on is similar or may be that of a conventional bottom. This being the case, it is not deemed necessary to describe the other portion herein.

While but one form of construction of the invention is shown in the drawing and described in the specification, it is not desired to limit this

application to such specific form or in any other way otherwise than limited by the principles outlined and the scope of the appended claim.

Having thus described the invention, what is claimed is:

A folding box formed from a blank of cardboard or the like comprising a bottom having a pair of upstanding side portions hingedly connected thereto, end portions connected by square corners to said side portions and hingedly connected to said bottom, said corners provided with

diagonal perforated crease lines, said crease lines terminating in slits positioned in a diagonal manner and reverse to the first mentioned diagonal crease lines, said end portions having collars hingedly connected thereto, said collars being provided with tabs formed by means of slots placed therein, said tabs being coated on their under sides with an adhesive and affixed to the said end portion.

WILLIAM GLENELG PALMER.
